TIME RECORDER

Elmer G. Streckfuss, Cincinnati, Ohio, assignor
to The Cincinnati Time Recorder Company,
Cincinnati, Ohio, a corporation of Ohio

Application September 18, 1939, Serial No. 295,631

7 Claims. (Cl. 234—43)

My invention relates to time recorders, more particularly of automatic type and is concerned with automatic lateral shifting of the card tray.

I have illustrated my invention by application to the general type of tray locator or shifter, shown in the Yates Patent No. 1,698,905 dated October 30, 1928, it being the main object of my invention to apply power by means of a clock controlled power operated device to the shifter instead of relying on a clock movement to supply the power. My novel structure includes means which is adjustable as in a program clock for timing the movements of the tray so that as a desirable end, I may provide for in and out shifting of the card tray for morning, afternoon and overtime, as distinguished from employing the shifting of the card tray for days of the week and using a card abutment for selecting in-and out registrations for the said three working periods.

Among other objects of my invention is the combination with an automatic card tray shift locked against tampering movements of means for rendering the locking function ineffective to the end that a person authorized to do so, may position the card tray irrespective of the automatic device.

The above and other advantages to be noted I accomplish by that novel structure and arrangement of which an example is illustrated in the drawings and will be described.

Refer to the claims that follow this description for a statement of the novelty inherent in said example.

Fig. 1 is a front elevation with the casing removed, and parts broken away.

Fig. 2 is a section taken along line 2—2 of Fig. 1.

Figs. 3 and 4 are respectively a front elevation and a plan view of a time recorder in which my improvements are incorporated.

Fig. 5 is a section taken along line 5—5 of Fig. 2.

Fig. 6 is a section taken along line 6—6 of Fig. 5.

Fig. 7 is a section taken along line 7—7 of Fig. 5.

Fig. 7a shows an alternate position of the parts seen in Fig. 7.

Fig. 8 is a detailed front elevation of an improved lever employed for shifting the card tray.

Fig. 9 shows an alternate position of the parts seen in Fig. 8.

Throughout the drawings I have omitted certain mechanisms whose functions are not essential to an understanding of my present invention. In the machine illustrated the operation of all 55

mechanism is entirely automatic, there being no hand lever or other device to which the regisree must apply manual effort to affect an imprint or registration of the time upon a card.

Referring to Figs. 1 and 2, a synchronous electric motor 10, operating through a suitable train of reduction gears indicated at 11, drives the shaft 12. Shaft 12 has at its outer end a gear 12a meshing with gear 13 to drive the vertical shaft 14. At its upper end the shaft 14 has a gear 14a which meshes with gears 14b and 14c to drive the time indicator 15a on the clock face. To clarify the drawings the lower portion of shaft 14 has been broken away but it will be understood that the said shaft may extend downwardly to control the type wheels 15 and other mechanism not a part of my present invention.

The shaft 14 has a gear 16 by which the large disc 17 is driven in timed relation with the indicator 15a through gear 16a, shaft 16b, pinion 16c and gear 16d. The gear 16d and disc 17 are fixed to a shaft 17a which is suitably journaled in the frame.

The disc 17 is provided with slots or openings 18 adapted to receive a series of lugs 19 which may be retained therein at desired circumferential intervals by screws 18a having nuts 18b.

With the arrangement shown the disc 17 is timed to make one revolution per day. An arm 20 pivoted to the frame at 20a has a downward projecting finger 20b and as the disc 17 revolves the lugs 19, striking projection 20b, lift the arm 20 slowly upward. As the lugs pass the projection the arm 20 will drop to its normal position and in so doing will each time set into operation my improved mechanism for changing the lateral position of the card tray as will be presently described.

The card tray, indicated at 21, is slidably mounted on the rods or shafts 22 and 23 and has depending side members or ways 21a which are channel shaped in cross section and serve to guide the card to a position between the type wheels 15 and the printing hammer 24. An abutment plate 25 slidable in the ways 21a, limits the depth to which the card may be inserted in the tray and thus determines the vertical placement of the imprint on the card. The position of the abutment plate is controlled by a cam 26 which has a follower 26a located on an arm 27, said arm being pivoted to the frame at 27a and having at its other end a rail or bar 27b upon which the stud 25a (extending from the abutment plate 25) rests.

When a card is inserted in the tray the abut-

ment plate 25 and arm 27 will be moved slightly downward, due to a lost motion arrangement incorporated in arm 27 but not shown in the drawings. The lost motion is utilized to close a switch 28 completing a circuit to a solenoid 29. Solenoid 29 attracts plunger 29a against tension of spring 29b to rock the hammer shaft 23, through link 30 and lever arm 23a thus actuating hammer 24 and forming an imprint on the card. This arrangement is described and claimed in my co-pending application Serial No. 219,438, filed July 15, 1938, and forms no part of my present invention, being merely incidental to a description thereof.

Pivoted attached to the arm 20, a rod 31 is arranged to lift a member 32 being fixed thereto by bracket 31a. As seen in Fig. 2, the member 32 is slotted at its upper end as at 32a where it is slidably mounted on a stud 32b fixed in the frame. As best seen in Fig. 7 the member 32 is also slotted as at 32c at its lower end where it is guided by a shaft 33 having a ratchet wheel 34 mounted thereon. A pawl 35 for advancing the wheel 34 is pivoted at 35a to the member 32. Mounted beneath the wheel 34 and arranged to be closed thereby is an electrical switch 36, said switch having an insulated contact with the wheel and being supported by a bracket 36a fixed to the bearing standard 33a.

As seen in Fig. 7 the parts are shown in their normal or inoperative position. As here shown the weight of member 32 and the linkage connected therewith rests upon the wheel 34 by virtue of the block 32d. Backward movement of the wheel is here prevented by a pawl 37 which pawl is mounted by means of bracket 37a to a cam operated lever 38 the purpose of which will be presently described.

As the member 32 and its associated parts are lifted upward by action of one of the lugs 19 striking the projection 20b of arm 20, the pawl 35 will be brought into a position suitable for advancing the wheel 34. When the lug 19 passes projection 20b permitting arm 20 and member 32 to drop, the wheel 34 will be advanced to the position seen in Fig. 7a where the tooth 34a has closed the switch 36. At this position of the parts the weight carried by member 32 is imposed upon wheel 34 by the pawl 35 and block 32d and as these members tend to rotate the wheel in opposite directions, it will be temporarily held from rotation. To prevent any tendency of the wheel to spin or travel too far during rotation, a spring member 34b is arranged to bear lightly against the wheel at all times. The pawls 35 and 37 may be equipped with light springs 35s and 37s respectively to urge engagement with the ratchet teeth.

Closing the switch 36 energizes a motor 39, which motor, operating through a train of reduction gears contained in housing 39a, drives shaft 40 and the cam 41 fixed thereon. The cam 41 depresses lever 38 against tension of spring 38a and the motor continues to run until cam 41 has made a complete revolution and its high point 41a has passed the follower or roller 38b at which time the spring 38a will return lever 38 to the position shown. The pawl 37, being carried downward with lever 38, will engage beneath the tooth 34c of the wheel and upon the upward movement or return of arm 38 will carry the wheel 34 to its normal position as in Fig. 7 permitting the switch 36 to open and stopping motor 39.

Referring now to Fig. 2 the lever 38 is pivoted

or trunnioned in the frame as at 38c and has a forwardly extending arm 38d which will be carried upward as cam 41 depresses the follower 38b.

5 Pivoted to 40a to the arm 38d a link 41a is arranged to rock the arm 42 which arm carries a pawl 43 adapted to engage and advance a ratchet wheel 44, said wheel being moved one tooth at each operation of the arm. Fixed to 10 rotate with the ratchet wheel a barrel cam 45 engages a pin or stud 46 to move the lever arm 47 by a mechanism to be described. The cam track is arranged to move lever 47 to the right (Fig. 1), against tension of spring 48, as the cam is advanced. After the lever has reached its extreme right hand position further rotation of the cam will bring into position a cross-track in the cam permitting the spring 48 to return the lever to its extreme left hand or starting position.

15 20 Pivoted to the upper end of lever 47, a link 49 is attached at its other end to the card tray 21 so that movement of the lever will result in proportionate movement of the card tray.

From the foregoing it will be apparent that 25 the function of each lug 19 on disc 17, is to set into operation a train of mechanism to change the position of the card tray.

The barrel cam 45 and its appurtenances as above briefly described is fully described and 30 claimed in the Patent No. 1,689,905 issued to James W. Yates, October 30, 1928, and its detailed construction forms no part of my present invention.

It is desirable to provide means whereby the 35 card tray may be shifted temporarily to any position desired, regardless of the position of the barrel cam. The arrangement which I have conceived to accomplish this object is one of the features of my invention.

In my improved device the lever 47 is mounted at its lower end on a shaft 50 being free to turn thereon and retained in position by collars 51 and 52 as seen in Fig. 2. Fixed in the lever 47 a stud 53 having a large head retains a second lever 54 which is slotted as at 54a to permit a 40 sliding relation between the two levers. Near the lower end of lever 47 a second stud 55 fixed therein engages the slotted portion 54b of lever 54 and serves to guide same in proper alignment. 45 A tension spring 56 fixed at one end to lever 47 and at its other end to lever 54 urges the levers to the relative position as seen in Figs. 1 and 8. The stud or roller 46 which engages the barrel cam is fixed to a short upstanding arm 57 which 50 arm may be fixed to shaft 50 and has a rearward extending pin or stud 58 which stud is of sufficient length to be engaged by the straight slotted portion 54b of lever 54. Lever 54 has an enlarged opening 54c communicating with the 55 slotted portion 54b already mentioned.

With the position of levers 47 and 54 as seen in Figs. 1 and 8 the card tray will be locked against any manual effort to shift it from its normal position as determined by the barrel cam. This is due to the locking effect of the pin 58 60 engaging slot 54b thereby forming a rigid connection or relationship between the levers 57 and 47. If, however, the lever 54 is pushed downward against tension of spring 56, the enlarged opening 54c of this lever will permit manual movement of the card tray as the pin 58 is no longer engaged by the lever and movement of the tray is not restricted by the barrel cam.

As an expedient and tamper proof means for shifting lever 54, I provide therein a stud 59 ex-

tending forwardly. Cooperating with this stud a lever 60 pivoted at 61 on the frame has a forward bent portion 62. On the casing or cover 63 is a cylinder lock 64 having fixed at its inner end an arm 65 having roller 66. As seen the roller 66 is arranged to bear on the lever 60 so that if a key is inserted in the lock and turned clockwise the levers 60 and 54 will be depressed as in Fig. 9, thereby releasing the card tray from its normal position due to the barrel cam.

An indicator arm or needle 67 is carried by the card tray being visible through a window 68 in the casing. The columnar position of the card tray is indicated by the position of the needle against an index card 69.

In the machine illustrated the cam 26 is advanced a step forward each day (by mechanism not shown or pertaining to my present invention) thus the week-day upon which the impression is made will determine the vertical placement of the imprint on the card. The columnar placement will indicate the "in" and "out" registrations and it will be apparent that any number of said registrations may be obtained by redesigning the barrel cam and employing a corresponding number of the lugs 19 on disc 17. Thus the barrel cam could be made longer and the helical track modified in pitch.

Having thus described my invention what I claim as new and desire to secure by Letters Patent, is:

1. In a time recorder a card tray, a transmission element forming part of means for moving the card tray laterally which element is self locking and linkage between said self locking element and the card tray which linkage is normally rigid but is susceptible to operator controlled movement to permit of yielding thereof.

2. In a time recorder a helical transmission means forming part of means for shifting a card tray and linkage actuated thereby and connected to the card tray, said linkage being normally rigid to hold the card tray in set position and lock controlled means for rendering said linkage means yieldable.

3. In a time recorder having a card tray mounted for lateral shift, power accumulating means operating by a setting and a release for actuating the card tray, an electric motor driven means for setting and releasing said power accumulating means, a switch for applying current to said motor, means for periodically closing the switch which is time controlled, and means for reopening the switch upon the release stroke of the power accumulating means.

4. In a time recorder having a card tray mounted for lateral shift, power accumulating means operating by a setting and a release for actuating the card tray, an electric motor driven means for

setting and releasing said power accumulating means, a switch for applying current to said motor, means for periodically closing the switch which is time controlled, and means for reopening the switch upon the release stroke of the power accumulating means, said electric motor driven means comprising the motor and a cam on the motor engaging the power accumulating means, the release of the latter being as it drops from the high point of the cam.

5. In a time recorder having a card tray mounted for lateral shift, power accumulating means operating by a setting and a release for actuating the card tray, an electric motor driven means for setting and releasing said power accumulating means, a switch for applying current to said motor, means for periodically closing the switch which is time controlled, and means for reopening the switch upon the release stroke of the power accumulating means, the means for periodically closing the switch comprising a time controlled moving member having settable elements therein, means engaged by said settable elements, the arrangement being such that power is accumulated and released during said engagement, and connections from said means to the switch whereby the operation thereof is upon the release of said means.

6. In a time recorder having a card tray mounted for lateral shift, power accumulating means operating by a setting and a release for actuating the card tray, an electric motor driven means for setting and releasing said power accumulating means, a switch for applying current to said motor, means for periodically closing the switch which is time controlled, and means for reopening the switch upon the release stroke of the power accumulating means, said switch closing and reopening means comprising a ratchet, the teeth of which engage movable elements of said switch, said means for closing the switch including a pawl engaging said ratchet, and the switch reopening means including a pawl also engaging said ratchet.

7. A linkage for connecting a card tray shifting transmission to a card tray comprising a pivoted lever connected at its free end to the card tray, a sliding member on the lever having means for engaging said transmission, pin and slot connection between the lever and the member at two spaced intervals, one of said pin and slot connections being arranged to be discontinued upon movement of the sliding member in one direction leaving the sliding member free to pivot on the lever at the other connection, lock controlled means for sliding the sliding member in said one direction, and means for normally maintaining said sliding member in its other position.

ELMER G. STRECKFUSS.
